UNITED STATES PATENT OFFICE.

EMMA M. VENESS, OF MILLERS, NEW YORK.

KNITTING-NEEDLE.

1,270,993.

Specification of Letters Patent.

Patented July 2, 1918.

Application filed September 24, 1917. Serial No. 192,942.

To all whom it may concern:

Be it known that I, EMMA M. VENESS, a citizen of the United States, residing at Millers, in the county of Orleans and State 5 of New York, have invented certain new and useful Improvements in Knitting-Needles, of which the following is a specification.

The object of this invention is to provide a new and improved needle for knitting and 10 a process for knitting with said needle.

These and other objects of the invention will be illustrated in the drawings, described in the specification and pointed out in the claims at the end thereof.

15 In the drawings,

Figure 1 is a perspective view of the needle enlarged and partly broken away.

Fig. 2 is a perspective view of the ends 20 of two of the needles showing them in the position they occupy in making the first step of the stitch.

Fig. 3 shows the ends of the needles in the second step in the making of the stitch.

Fig. 4 shows the ends of the needles in the 25 third step of the making of the stitch.

Fig. 5 shows the needles in the fourth or last step which they take in the making of the stitch.

Fig. 6 shows the ends of the needles in 30 position to form a purling stitch.

In the drawings like reference numerals indicate like characters.

In the drawing reference numeral 1 indicates the knitting needle magnified. The needle is substantially rectangular in cross section and has rounded corners or edges. The width of the needle is somewhat greater than the height or thickness of the needle. At the forward end of the needle the needle is cut away or recessed as indicated at 2 to form a hook 3, the upper edge of which is rounded so that it will be free from corners or points on which the yarn might catch. The needle is provided with a point 4, just back of which the recess is formed. The hook of the needle is slightly undercut to insure the more positive engagement with the yarn. The needle is made rectangular or with flat sides so that it can be held positively with the side containing the hook either up or down.

In knitting open work by hand, two needles are regularly used while in knitting round or closed work, four or more needles will be used.

In hand knitting a series of stitches is formed on one needle which will be referred to as the passive needle, P, and these stitches are removed one at a time from the passive needle by the active needle A and in the removal of each stitch a new stitch will be formed by looping the yarn through the 60 stitch that is removed.

The loop is held on the active needle and becomes a complete stitch. As each stitch is 65 removed from the passive needle it is locked by the new stitch and passes into the finished work and the new stitch is formed and retained on the active needle and this is repeated until all the stitches have been removed from the passive needle and a new 70 row of stitches has been formed on and is carried on the active needle, each stitch being locked by the needle which holds it. After the work is completely removed to the 75 active needle, the active needle then becomes passive and the needle which was previously used as the passive needle will be used as the active needle in forming and holding the 80 next row of stitches.

It will be understood that heretofore in knitting, two different systems or processes have been used in which round needles without hooks are regularly used. One of these systems is the so-called English system in which the active needle and the yarn 85 are held in the right hand and the passive needle is held in the left hand. The other system is the so-called German system or process in which the active needle is held 90 in the right hand and the yarn and passive needle are held in the left hand.

In the practice of my invention the active needle is held in the right hand and the passive needle and the yarn are held in the 95 left hand and to that extent my invention is similar to the so-called German method of knitting. My invention consists more especially in the use of a hooked needle in forming the loop and for the purpose of 100 illustrating the method of knitting, I have shown the loop in process of formation in four successive steps shown in Figs. 2, 3, 4 and 5. In Fig. 2, reference character 5 indicates the end loop on the passive needle. 105 Through this loop is inserted the active needle until it engages with the free yarn 6. As soon as the hook of the needle has engaged the yarn the needle is drawn straight back and the yarn is drawn through the loop 110

with it forming the new loop 7 as shown in Fig. 3.

In forming the new loop the left hand is rocked to bring the yarn into the path of the hook and the needle is then tipped to bring the hook into engagement with the yarn and the needle is then drawn straight back through the loop. Because of the hook it is only necessary to tip the needle 5 through a small angle and then draw it straight back. If the hook were absent it would be necessary to tip the needle through a large angle, first into engagement with the yarn and then to poke the yarn through the 10 loop as is done in both the so-called English and German method. In this way the 15 operation of knitting is greatly simplified and more work can be done in the same time because the movements are simpler and the 20 dropping of stitches is prevented. After the new loop is formed in this manner the 25 point of the active needle is then raised and pushed forward above and along the top of the passive needle and the old loop 5 is pushed off of the passive needle as part of the finished knitting, the new loop being carried on the active needle.

In like manner each successive loop is removed from the passive needle and a new 30 loop in addition thereto is formed on and carried on the active needle.

As will be seen from an inspection of Figs. 2, 3, 4 and 5 that the passive needle 35 is held with the hook down and the back up. The back of the needle is smooth so that the successive loops can easily slide off therefrom while it is held up. The hook is turned down on the passive needle so that 40 it will not engage with or interfere with the removal of the loops. The active needle is held on its side in the various steps in the formation of the new loop; the faces of

the two needles being kept substantially at right angles to each other.

In purling the hook of the active needle 45 is turned down and the smooth side of the active needle is inserted under the yarn at the right of the yarn and the hook is then inserted through the end loop of the passive needle above the passive needle as shown 50 in Fig. 6, after which the free yarn is brought around under the active needle and caught in the hook and the active needle is then drawn back through the loop drawing the 55 yarn with it forming a new loop after which the old loop is drawn off of the passive needle.

I claim:

1. A knitting needle having a substantially uniform non-circular cross section, 60 said needle having a point at one end thereof and having a hook formed therein near the pointed end on one side.

2. A knitting needle having a substantially uniform rectangular cross section, 65 said needle having a long, slender and sharp point at one end and having a shallow hook formed therein near the pointed end on one side, the other side of the needle being left flat.

3. A knitting needle having a substantially uniform rectangular cross section, 70 said needle having a long, slender and sharp point at one end and having a shallow hook formed therein near the pointed end on one side, the other side of the needle being left flat, said hook being formed by cutting a shallow recess in one side of the needle.

In testimony whereof I affix my signature in the presence of a witness.

MRS. EMMA M. VENESS.

Witness:

ELEANOR M. CORCORAN.
